UNITED STATES PATENT OFFICE.

JAMES A. MCINTOSH, OF DETROIT, MICHIGAN, ASSIGNOR TO THE LEES-BRADNER COMPANY, OF CLEVELAND, OHIO, A CORPORATION OF OHIO.

GEAR-TOOTH GAUGE.

Application filed June 19, 1920. Serial No. 390,089.

This invention relates to gauges for indicating the condition of gear teeth being cut. At the present time, in setting up a machine for cutting gear teeth, it is the practice to 5 cut a gear and then roll the gear into contact with another gear and solely by observation and feel determine whether the teeth are accurately and properly cut to get the proper meshing action between the teeth of 10 the two gears. It is the principal object of the present invention to provide an instrument which will register any inaccuracies by thousandths of an inch or less, in a gear which is not cut true.

15 In the drawings,—

Fig. 1 is a plan view of the instrument.

Fig. 2 is a side elevation of the same, partly in section.

Fig. 3 is a section on the line 3—3 of 20 Fig. 2.

a designates a base that may be bolted thru the slot *b* to a suitable support. This base is recessed to form a slide-way *x* in which travels the slide *c* actuated by the 25 winged screw *d* against the resistance of the spring *e*. This slide is provided with an upstanding post *f* which journals a reel *g* adapted to take a steel band *h* fastened thereto by the clamping block *i*. The 30 center (considered in the direction of its thickness) of this band upon this reel registers substantially with the pitch circle of the gear *j* which is bolted to the externally-threaded hub *y* of the reel by means of the 35 nut *k*. The opposite end of the band *h* is clamped to the bed by the block *m*. A torsional spring *n* has one leg attached to the 40 slide *c* and the other to the reel *g*. (See Fig. 2.) This keeps the reel turned to draw 45 the band taut at all times. The object of this band is to cause the gear *j* to so rotate, when the slide *c* is moved inwardly against the tension of the spring *e*, that it will develop its pitch circle into a straight line.

At *q* is shown a major slide adapted to be 45 adjustably slid in ways *r*—*r* in the base *a*. The position of the slide *q* in the ways may be fixed by screws *q*—*q*. The slide *q* carries supports *o*—*o*, provided with rectangular guideways *o*—*o* in which is mounted 50 for sliding movement transversely of the slide *q*, a minor slide *o*, provided with a traveling over a rack, the teeth travel over

point or projection *p*. The point *p* is shaped like a rack tooth and meshes with 55 the teeth of the gear *j*. A lever *z*, pivotally supported on the slide *q* at *z*, has one end in engagement with a notch *z* in the minor slide *o* and has the other and longer end in engagement with the stem 1 of an indicator 60 2, such as a Brown & Sharp indicator or any similar device. A centralizing mechanism is provided for normally maintaining the lever *z* and minor slide *o* in a central position and comprises a guide rod *t* supported on posts *u*—*u*, a sleeve *s* loosely slideable on the guide rod, and springs *v*—*v* between the ends of the sleeve *s* and the posts 65 *u*—*u*. The lever *z* is pivoted to the sleeve *s* at *z*. 70

When the gear *j* is rotated as above described, the teeth of the gear will mesh with the point *p* similarly as it would if it were one of the teeth of a rack.

The operation will be perfectly plain. 75 When the gear *j* to be tested is mounted on the post *f*, the slide *c* and the adjustable slide *q* are preferably in the positions shown in Fig. 1, so that the point *p* meshes with the gear teeth. Before the nut *k* is tightened, the gear *j* is turned by hand counter-clockwise until one of its teeth is in engagement or contact with the surface *p* of the point *p*, this contact being resiliently maintained by the centralizing mechanism above 80 described, as will be understood. Now, by turning the screw *d* in one direction, the slide *c* is caused to move forward, the spring *e* taking up any lost motion. This unwinds the band *h* from the reel, causing the 85 gear *j* to roll in the same way it would roll if it were rolling on a plain surface on its pitch circle, this operation serving to put the torsional spring *n* under tension so that it maintains the band *h* taut as rolling of the reel and unwinding of the band takes place. When the screw *d* is turned in the other direction, the slide *c* is thereby moved 90

back towards its starting position, and the torsion spring *n* rotates the reel *g* and gear in the opposite direction and thus takes up 95 any slack in the band *h* which would otherwise occur therein. This is the movement the gear would take in traveling over a rack having teeth accurately cut. Instead of 100 traveling over a rack, the teeth travel over

the point p connected with the indicating lever. Since the surface p^1 of the point or tooth p is held in contact with the adjacent tooth face as above described, the point or tooth p will be moved if the tooth face is inaccurate, and such movement will cause the lever z to rock and the amount of its movement will be registered on the dial of the indicator 2, thus indicating in fractions 10 of an inch the amount of inaccuracy in the gear tooth face. In this way one face of each tooth, one after another, can be tested. Then by loosening the nut k and rotating the gear clockwise until the other surface 15 p^2 of the point or tooth p is engaged by the gear teeth, any inaccuracies in the opposite teeth faces may be indicated. With this accurate knowledge the operator may then 20 adjust the parts of the gear cutting machine 2 to properly cut the succeeding gears or re-cut the tested gear. In this way accurate gears may be cut without in any way depending upon the human element to detect errors. This will result in much better gears and 25 much better running of the machinery containing sets of gears.

There are several well recognized circles in connection with calculating gears; for instance, there is an addendum circle, a root 30 circle and any number of pitch circles the diameters of which depend upon the slope or pressure angle of the surfaces (in this case the surfaces p^1 and p^2) with which the gear to be tested is meshed. It will be obvious 35 that my instrument, especially the band, could be used to develop any one of these circles by simply changing the reel to accord with such circle. Hence I am not limiting myself in the claims directed to the specific 40 means for developing a pitch circle to a single circle. I have, therefore, seen fit to refer to such a circle generically as one of the gear teeth circles.

What I claim is:

45 1. In a machine for the purpose specified, the combination of a gear support, means for causing a gear on said support to roll and develop a part of its pitch circle into a straight line, and testing means including a 50 device yieldingly supported at the side of the tooth to be tested and in engagement therewith, so that, when the gear tooth is accurately cut, the said means will not be to any appreciable extent displaced when the 55 gear is caused to roll over the same in developing its said pitch circle, but, when the gear tooth is inaccurately formed, the same will be displaced from its normal position.

60 2. In a device for the purpose specified, the combination of means for supporting a gear and causing it to roll and develop a part of its pitch circle out in a straight line, a testing tooth, means for yieldingly supporting said tooth in a predetermined position with one face thereof adjacent to the

face of a gear tooth of a gear on said supporting means so that, if the latter is accurately shaped, the said testing tooth will not be appreciably displaced when the gear tooth rolls over the same as the gear develops its pitch circle, but, when the gear tooth is inaccurately formed, the same will be displaced from its predetermined position, and means actuated by said testing tooth for indicating such displacement of the gear tooth. 75

3. In a device of the character described, the combination of means for supporting a gear and causing it to roll and develop a portion of its pitch circle into a straight line, a tooth in the form of a rack tooth, means for yieldably supporting said tooth in a predetermined position with one face thereof adjacent a gear tooth of a gear on said supporting means, so that when the latter is accurately formed it will roll over the rack tooth without appreciably displacing the same when the gear develops its pitch circle into a straight line, but, when the gear tooth is inaccurately formed, the said rack tooth will be displaced, and indicating means to 85 show the displacement of said rack tooth. 90

4. In an instrument of the character specified, the combination of means for supporting and rolling a gear to cause it to develop a part of its pitch circle into a straight line, 95 a lever, resilient means for yieldingly holding the lever in a normal position, a pointed member connected with the lever, and adapted to mesh with the teeth of a gear on the supporting means in developing its pitch circle into a straight line whereby any irregularities in the teeth cause the lever to move to indicate the presence of such irregularities. 100

5. In an instrument of the character specified, the combination of a support, means for developing a portion of the pitch circle of a gear supported on said support into a straight line, a member adapted to mesh with said gear, a lever pivotally mounted on said support and operatively connected to said member, means for holding said lever in a predetermined position, and an indicator engaging the other end of the lever to indicate any irregularities in the gear teeth actuated by the irregular teeth of the gear in displacing said lever. 110

6. In an instrument for the purpose specified, the combination of a support, means for causing a gear supported on said support to develop a portion of its pitch circle into a straight line, a member adapted to engage between the teeth of the gear in making such movement, an indicating lever pivotally mounted on said support, means for yieldably holding said lever in a predetermined position, and an indicator engaging the other end of the indicating lever in a relation to multiply the movement from the point to the indicator stem contact whereby 125 130

any irregularities in the gear teeth cause the indicating lever to move and multiply the movement and communicate the same to the said indicator.

5. 7. In an instrument for the purpose specified, the combination of indicating means for testing gear teeth for irregularities, and means for supporting a gear to be tested and causing it to roll and develop a portion of 10 one of its gear teeth circles into a straight line, the latter comprising a slide on which the gear is mounted rotatably, a reel concentric with the gear, and a band fixed to the reel periphery in registry with said circle of 15 the gear and adapted to unwind as the slide is caused to travel and thereby constrain the gear to develop its said circle into a straight line.

8. In an instrument for the purpose specified, the combination of indicating means for testing gear teeth for irregularities, and means for supporting a gear to be tested and developing a portion of one of its teeth circles into a straight line, and comprising a 20 slide, a reel rotatably mounted on the slide and arranged to be secured to the gear to be tested, a band carried on the reel, the band, the reel and the gear being arranged so that the reel periphery is in registry with 25 the said circle of the gear whereby movement of the slide causes the gear to develop its said circle into a straight line to permit the operation of the tooth testing means.

9. In an instrument for the purpose specified, the combination of a slide, a reel mounted on the slide, a band fixed onto the reel and winding about the periphery of the reel, the band being arranged to be in substantial 30 registry with one of the gear teeth circles 35 of a gear to be tested adapted to be secured to and in registry with the said reel, and a spring for operating upon the reel to pull the band taut about the reel periphery.

10. In an instrument for the purpose specified, the combination of indicating means for testing gear teeth for irregularities, and means for supporting a gear and causing it to develop a portion of one of its gear teeth circles into a straight line, the latter comprising a slide adapted to support said gear, means for advancing the slide, a reel rotatably mounted upon the slide, a band encircling a portion of the periphery of the reel and having one end fixed, and a torsional spring for taking up the slack of the band on the reel, the said band being in substantial registry with the said circle of said gear.

11. In apparatus of the character described, the combination of a support, a stud mounted thereon and supporting a roller and adapted to support a gear to be tested, a flexible member connected to said support and roller, means for moving a gear supported on said stud to effect winding of said

flexible member on and off said roller, a lever, lever operating connections between a tooth of the gear at one end of the lever, and means operated by the movement of said lever to indicate the inaccuracies of the 70 gear teeth.

12. In apparatus of the character described, the combination of a support for a gear permitting a gear supported thereon to be translated and rotated, a separate support 75 associated with said first mentioned support, a tooth engaging member mounted to move on said separate support in a direction parallel to the translatory movement of the gear, and indicating means operatively 80 connected with said tooth engaging member to indicate the amount of movement thereof resulting from inaccuracies in the gear teeth.

13. In apparatus of the character described, the combination of a support for a gear, an indicating means on said support, a tooth engaging member movably mounted on said support and actuated by inaccuracies 85 in the teeth of a gear on said support, guide 90 means permitting translatory movement of the gear in a direction parallel to the direction of movement of said tooth engaging member and rotary movement about its axis, and operative connections between said tooth 95 engaging member and said indicating means.

14. In apparatus of the class described, the combination of a support for a gear to be tested, means associated with the support for translating and rotating a gear on said 100 support, a separate support associated with said first mentioned support, a gear tooth engaging member on said separate support mounted for movement in a straight line, and indicating means operatively connected 105 with said tooth engaging member to indicate the movement thereof resulting from inaccuracies in the gear tooth.

15. In a device of the class described, means for supporting a gear and causing it to roll and to develop a portion of its pitch 110 circle in a straight line, a movable contact device supported and constrained to move in a straight line, and means for holding said device in yieldable engagement with the face of a tooth of a gear on the support, whereby, when the gear tooth face is accurately formed, the gear will roll without appreciably moving the contact device, but, when the gear tooth face is inaccurately 115 formed, the device will be moved, and means for indicating the movement of said device.

16. In apparatus of the class described, means for supporting a gear which is to be tested and causing it to roll on its pitch circle without slipping, a testing member provided with a surface having the shape and position relative to a gear on the supporting 125 means of a rack tooth face in meshed engagement with a tooth of the rolling gear,

the testing member being supported with said surface held yieldably in engagement with a tooth face of the supported gear and movable in a direction parallel to the movement of the center of the gear when rolling, whereby, when the gear tooth is accurately formed, it will roll without appreciably mov-

ing the testing member, but, when the gear tooth is inaccurately formed, will move it, and means for indicating the movement of 10 said testing member.

In testimony whereof I affix my signature.

JAMES A. McINTOSH.
